Patented Feb. 24, 1976

238,939

DASHBOARD HOUSING FOR A MOTORCYCLE OR THE LIKE

Joseph C. Weber, 1100 NE. 58th,
Oklahoma City, Okla. 73111

Filed Dec. 5, 1974, Ser. No. 529,685

Term of patent 14 years

Int. Cl. D12—11

U.S. Cl. D12—114

FIG. 1

FIG. 4

FIG. 2

FIG. 5

FIG. 3

FIG. 6

FIG. 1 is a front elevation view of a dashboard housing for a motorcycle or the like, showing the present design.

FIG. 2 is a top plan view thereof.

FIG. 3 is a rear elevation view thereof.

FIG. 4 is a right side elevation view thereof.

FIG. 5 is a bottom plan view thereof.

FIG. 6 is a left side elevation view thereof.

I claim:

The ornamental design for a dashboard housing for a motorcycle or the like, substantially as shown.
